UNITED STATES PATENT OFFICE.

OMAR J. HOTALING, OF EAST ORANGE, NEW JERSEY, ASSIGNOR TO AMERICAN NEWS-VENDER CORP., OF NEW YORK, N. Y., A CORPORATION OF NEW YORK.

DESIGN FOR A NEWSPAPER-VENDING CABINET.

54,841.

Specification for Design.

Patented Apr. 13, 1920.

Application filed March 15, 1919. Serial No. 282,990. Term of patent 7 years.

To all whom it may concern:

Be it known that I, OMAR J. HOTALING, a citizen of the United States, and a resident of East Orange, in the county of Essex and State of New Jersey, have invented a new, original, and ornamental Design for a Newspaper-Vending Cabinet, of which the following is a specification, reference being had to the accompanying drawing, forming part thereof.

The figure is a perspective view of a newspaper vending cabinet, showing my new design.

The design comprises a novel and ornamental shape or configuration of a cabinet, the main portion of which is rectangular in form and provided with a top constituting

a segment of a hollow cylinder, the lower portion of the cabinet comprising a projection having a curved rear face, the side walls of that portion of the cabinet having the curved face tapering downward toward forwardly projecting hook-shaped points. The front wall of the cabinet is provided with an opening of segmental circular form, and among other characteristics the design includes a novel representation of wording on the front, the letters of which are characteristic and of a novel or ornamental appearance.

I claim:

The ornamental design for a newspaper vending cabinet, as shown.

OMAR J. HOTALING.
